CLAIM

The ornamental design for tripod with instrument supporting head, as shown.

DESCRIPTION

FIG. 1 is a top front perspective view of a tripod with instrument supporting head showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof.

FIG. 1

FIG. 3

FIG. 2

FIG.4

FIG.5

FIG.6

FIG.7

UNITED STATES PATENT AND TRADEMARK OFFICE
CERTIFICATE OF CORRECTION

PATENT NO. : Des. 300,037

DATED : February 28, 1989

INVENTOR(S) : John A. Jones, L. Mark Marchus and Loren S. Hardy

It is certified that error appears in the above-identified patent and that said Letters Patent is hereby corrected as shown below:
